METHOD AND APPARATUS FOR MAKING
BAGS

Thomas Earl Coty, Watertown, N. Y.

Application September 15, 1934, Serial No. 744,229

5 Claims. (Cl. 93—22)

My present invention relates to bag manufacture, particularly paper bags, though its use with other tissues is not to be excluded. The present invention concerns the method or art of manufacture, and the machine the operation of which exemplifies that method.

In making bags in which the bottom is folded and pasted in place, it is a common practice to cut short slits parallel to the sides of the bag-blank in order to facilitate the folding. Side folds or flaps and longitudinal folds are then formed by opening the bottom and turning back one of the longitudinal folds, giving the bag when completed the well-known "diamond fold". There have been difficulties attendant upon this construction, particularly in making the bottom tight at the roots of the slits, or when the slits are not used, as is possible with some forms of bag, in securing the corners of the folds in place at that location.

Heretofore no machine has been devised for applying paste between the side folds and the part of the web forming the bottom of the finished bag. In consequence pockets are formed (by turning over the side folds) which may become filled with cement or other materials, usually pulverulent, contained in the bags. When the bag has been filled and is then dropped or tossed around, the contents acts by its weight as a wedge and gradually forces the flaps apart until a leak is formed, or even a rent which ruins the bag. This defect has heretofore been thought unavoidable, and so far as I know, no way has been found to cure it.

I have found it possible to correct this difficulty substantially completely, by applying paste to the surface of the side flaps referred to, so that they are firmly attached to the adjacent parts of the web forming the bottom of the bag. This may be done by hand, but of course such an expedient is inadmissible and inefficient. While a device for that purpose would apparently necessarily be complex and costly, by the simple mechanism described and illustrated in this case it is possible to effect the result without slowing up the manufacture, and without increasing operating or labor costs, or overhead except by the small amount of interest and depreciation on the mechanism; while, on the other hand, the invention makes it possible to make a three-ply bag which is stronger than a four-ply bag made in former ways, as careful tests have shown, and thus to make a large saving in paper, paste and labor.

My improved method of manufacture, there-

fore, consists in opening the end of the bag-blank so as to form side folds and longitudinal folds for forming a closure, applying paste between the side folds and the other parts of the web forming the closure, and then turning and pasting the folds to complete the operation. Other more specific details of the method will be found in the claims. Mechanically the means for practicing the improvement in the art consists of means for forming side-folds and longitudinal-folds in a bag-closure; means for applying paste between the side folds and the other parts of the web forming the closure, and means for completing the closure. More detailed explication will be found in my claims. I have shown only a bottom closure, as that is sufficient to make the matter clear. The multiwall valve-bag in common use has both ends closed, and the invention is available for the valve-end also.

The accompanying drawings show an embodiment of the mechanical features of my invention, by which the improvement in the art may be practiced:—

Figure 1 is a diagrammatic plan showing a bag passing through this part of the apparatus.

Figure 1a is a view of a bag having no slits, with the invention applied thereto.

Figure 2 is a side elevation partly in section and partly diagrammatic of a machine for carrying out the process indicated in Figure 1.

Figure 3 is a side elevation of some parts shown in Figure 2, also partly in section.

Figure 4 is an end view of the pasting mechanism.

Figure 5 is a separate detail view showing the pasters or pads in two positions.

Figures 6 and 7 are perspective sketches on a larger scale of one of the pasting mechanisms, with the cam operating it, and the universal joint which I have devised for this movement; Figure 6 showing the pad in pasting position, and Figure 7 when not so acting.

Figure 8 is a sketch of a completed bag.

I have indicated certain parts of a "bottomer" in order to make clear a desirable location for the mechanical part of my invention; the bottomer is of the type shown in Letters-Patent to A. C. and T. E. Coty, Serial Number 1,770,972, dated July 22nd, 1930, though other machines may be used.

In Figure 1, A is the bag in its first position as it enters the new pasting mechanism hereinafter described, and successive positions are indicated at A¹, A², A³, and A⁴; B is the side flap of the bag, and C is the part of a flap which cor-

responds to the slotted part of the web. At E I have shown a guide mechanism which acts to turn back the flaps C until they are in substantially a vertical position, and at the same time 5 lifts the side fold B so that the pasting mechanism may pass thereunder, as hereafter indicated. This position is shown at A¹. At A² the pasting mechanism has applied paste at F, F, while the flap C is still turned up. At A³ a guide H has 10 been interposed, which turns down the flap C so that the side fold is secured to the other parts of the web forming a closure. The bag then passes on to A⁴; the paste pad of the bottomor here applies the paste at G, so that when the 15 two flaps are folded over the one on the right will be superposed on the one on the left to form a tight closure.

In Figure 1a it is obvious that the guides E and H will not be needed inasmuch as there is 20 no flap C to be turned up; and the guide E need not be employed for the purpose of lifting the flap B. As will be obvious from the shape of the pasting mechanism (see Figures 5, 6 and 7) the paste pads themselves will lift the side flap 25 B sufficiently, and the guide E for this form of the bag would have no function, though the mechanism would operate with it in place, on bags like 1a.

In Figure 2 I have shown the mechanism arranged in place between the opening mechanism for the bag-bottom and the folding devices of a bottomor such as the one already referred to, as shown for example in Figure 11 of Patent No. 1,770,972. The cylinder M is mounted on 30 the main power-shaft of the bottomor. By means of the gear M¹ indicated diagrammatically the cylinder K² is operated, this being the creaser cylinder of the bottomor, which bears that reference letter in the patent referred to. M¹ also 35 drives the pulley M⁷, around which one set of the belts N passes; as shown in Figure 4, there are two sets of these belts or tapes N. The gear M⁸ on the shaft of the cylinder M acts to drive these cylinders or gears. On the other side of 40 the cylinder M the gear M² meshes with M⁸ and drives the gear M⁹ around a pulley upon which the belts pass, and that gear drives the gear M³ which operates the cylinder J of the opening 45 mechanism of the bottomor. The pulley M⁴ is loose on the shaft of the gear M³, and M⁴ is an ordinary belt-tightener mounted on an arm and having a spring (not shown) to press it 50 against the belt. The cylinder V carries the paste pads W¹, W², the construction of which will be described later, and these pads pass over the pasting mechanism O. A paste device has 55 a roll K running in a tank K³ and with a distributing drum K¹ is also used to apply the paste G shown in Figure 1, by well-known mechanisms not shown. It will be seen that the bag A enters 60 at the left between the cylinders I and J. It is shown already partly opened, the opening mechanism being that described in the patent already referred to. The bag then passes down between 65 cylinders J and J¹ over the cylinder L and beneath cylinder M⁶, having passed over the guide E for opening the edges C of the side folds B; pads W¹, W² are then operated, as presently to be described, and the blank then passes under the 70 guides H to turn down the flaps C and thence around the creaser cylinder K² to the folders of the bottomor.

Figures 3, 4, 5, 6 and 7 should be read together. I have not described the paste-pad-operating mechanism in connection with Figure 2,

because the parts are shown more plainly in the figures now considered.

Referring first to Figure 4, the pads W¹, W², are shown in the position which they will occupy when the paste is being applied beneath the folds 5 and the guides E have turned back the parts C of the flaps B so as to be out of the way of the paste-pads. These pads (Figure 4), are mounted upon a bar W, and as will be seen, may be moved along the bar to adjust them for different positions as regards the width of the bag being made. The disks V constitute a "cylinder", as is well understood in bag-machines, and the bag A is stretched from one to the other of the disks, the closure passing through the machines in lateral 10 position. The bar W is fixed to the disks V¹, V¹, shown on the right and left of Figure 4, and these are mounted on the shaft P, which carries the disks or cylinder V, and are secured to disk V² by a bolt V³, moving in the slot V⁴ shown in 20 Figure 3, which adjusts the position of the pads W¹, W², circumferentially with reference to the disks V, V, and so determine their relation to the bag-bottom. It will be seen that this gives a complete adjustability around the circumference of the disk within the necessary limits, and also a lateral adjustment to adapt them to different widths of bag blank.

The pads are operated, as will be seen in Figures 6 and 7, by means of a cam-roller V⁵ running on a cam V⁶ and held in place by a groove in the disk V⁴, a split hub V⁸ serving to adjust the position of the disk and cam so that the paste pads W¹, W², will be actuated at the proper time. This construction is sketched in Figure 5, 35 which shows the two pads in solid lines in the non-pasting position, and in dotted lines in the position in which paste is being applied. The pads take the paste from the pasting device O, (see Figure 3), in which the roller O¹ driven by 40 the roller O² runs in the paste in the tank, and a distributing roller O³ is in contact with the roller O¹, and also is engaged by each of the pads W¹, W², as they pass it. The roller O³ is carried on arm O⁴, which is spring-pressed towards the cylinder V, the spring being adjustable 45 by a lock-nut O⁵.

Turning now to Figures 6 and 7, the construction of the pads and the means of operating them will be readily understood. I will describe Figure 7 particularly, as 6 and 7 show the same mechanism and I have omitted some of the reference characters in Figure 6 in order to clarify that drawing. Figure 7 shows the non-pasting position. Here V⁴ is the outer disk as shown in 55 section in Figure 4, V⁵ is a cam, which is in general of circular outline having the raised portion or hump. The cam-roller V⁶ travels in the cam-groove, the position of the high parts of the cam with reference to the roller being adjusted by means of the bolt V¹³ shown in Figure 4 on the right. This cam operates an arm V⁸, which has a split hub V¹⁰, which may be tightened upon the shaft V⁷ by means of the bolt V¹¹. On the shaft V⁷ is a hub V¹⁰ which also is split 60 and is secured on the shaft by the bolt V¹¹. It will be seen that by easing the bolt it is possible to slide the hub V¹⁰ along the shaft V⁷, and in this way to regulate the stroke of the paste-pad W², approximating hub V¹⁰ to the stud V¹⁴ about 65 which the pad W² reciprocates, increasing the stroke. A rod V¹³ is secured in the hub V¹⁰ by means of the set-screw V¹². This rod makes a working fit with a bore in the block V¹⁴. A similar rod V²⁰ passes through the hub V¹⁰ of an 70

arm V^{18} , which carries a paste-pad W^2 . This rod V^{20} makes a working fit with the bore in the block V^{21} superposed on the block V^{14} , and is held in place by a set-screw V^{19} ; and this part of the 5 device beginning with the hub V^{15} oscillates by means of a hub V^{17} around the stud V^{16} , which is carried by a slide V^{25} on the bar W , as shown in Figure 4. This slide may be secured in place on the bar W by means of a bolt V^{26} .

10 As already stated, the hub V^{10} may be moved along the shaft V^7 in order to increase its distance from the stud V^{16} on which the arm V^{18} reciprocates and the slide V^{25} will be adjusted on the bar W so as to co-operate with the other parts 15 of this universal joint. The cam V^5 is stationary and the whole of this apparatus rotates with the cylinder V towards the observer in Figure 4 or to the right in Figure 2. As the shaft V^7 is thus carried around the cam V^5 , so long as the cam- 20 roller is on the circular part of the cam, the pad W^2 maintains the position shown in Figure 7. When, however, the roller V^9 is drawn by the rotation of the shaft around the cam as it is drawn along by the disk V constituting the cylinder, it reaches the high parts of the cam and turns the shaft V^7 towards the observer in Figure 7. This causes the rod V^{13} to press up on the block V^{14} and consequently upon the block V^{21} , thus pressing up the rod V^{20} , and presses the arm 25 V^{18} to the left so as to bring the pad into the position shown in Figure 6. As soon as the roller V^9 passes the high point of the cam, the pad W^2 is withdrawn to the position shown in Figure 7. The shaft V^7 in Figure 4 appears just 30 below the bar W . The cam-groove operates the roller V^9 positively at all times.

It will be seen that in these combined instrumentalities the pads W^1 , W^2 , are drawn over the paste-roller O^3 by the rotation of the disks V . 40 At the same time as the pads approach the position in which paste is to be applied between the side folds and the main web of the bag, the roller V^9 comes to one of the high points of the cam V^5 in Figure 7, and moves these pads into the 45 position shown in Figures 4 and 6 and in dotted lines in Figure 5, in which they make contact with the bag A , as already described. Upon passing further along, the pads are brought back to the full-line position shown in Figure 5. They 50 then are operated by the other hump of the cam V^5 so that they assume the position shown in Figure 6 as they pass over the paste-roller O^3 , then returning to the position shown in Figure 7.

It will be understood from Figures 3 and 4 that 55 there are two sets of the pads, being four in all, to accommodate the four positions of the paste F shown in Figure 1. The second set of pads being

exactly like the first and being operated by similar mechanism in the same way, it is unnecessary to describe them further.

The mechanism is so located with relation to the bottomer that its functions are performed 5 between the time of opening the flaps of the bottom of the bag and the time when the bag passes to the folding mechanism of the bottomer.

Figure 8 shows the bag as finally completed, 10 which does not differ in appearance from other well made bags, though of superior construction.

It is obvious that equivalent mechanisms could be devised which, while changing the form, would embody the invention herein described, and I aim 15 to cover such mechanism by the claims.

I claim:—

1. The improvement in the art of making bags from blanks, which consists in opening the end 20 of a bag-blank to form side folds and longitudinal folds; applying paste beneath the under sides of the side folds and the parts of the web employed in forming the closure, and then completing the closure with the longitudinal folds.

2. The improvement in the art of making bags from blanks, which consists in opening the end 25 of the blanks to form side folds and longitudinal folds; separating the side folds from the adjacent parts of the web employed in forming the closure of the bag; applying paste between the side folds and the adjacent parts of the web; returning the 30 side folds to position and completing the closure of the bag.

3. In bag-making apparatus, means for opening the end of a bag-blank to form side flaps and longitudinal flaps; means for applying paste beneath the under sides of the side flaps and parts of the web adjacent thereto which are employed 35 in forming the closure; and means for completing the closure of the bag with the longitudinal flaps.

4. In bag-making apparatus, means for opening the end of the blank to form side-folds and longitudinal-folds; means for separating the side folds from the adjacent parts of the web which are employed in forming the closure of the bag; means for applying paste between the side folds 45 and the adjacent parts of the web; means for returning the side folds to position; and means for completing the closure of the bag.

5. The improvement in the art of closing pasted bags, which consists in advancing a tubular bag-blank having unsecured side and end closure flaps; lifting the side flaps to a desired extent while the blank is advanced; applying adhesive under the lifted flaps; sealing the flaps by the adhesive; and then completing the closure. 50 55

THOMAS EARL COTY.
